REVERSIBLE BUCKLE

Herbert Buchsbaum, Chicago, Ill.

Application August 17, 1938, Serial No. 225,281

4 Claims. (Cl. 24—178)

The present invention relates to belt buckles, and particularly to a reversible belt and buckle construction in which the belt has both sides of such character that they may be used for the outside, or exposed, surface of the belt. For example, the buckle is particularly adaptable to belts which have one side of one color and the opposite side of another color.

It is the principal purpose of this invention to provide a simple buckle construction of this character wherein the buckle is made of two side bars and three cross bars connecting the side bars, the cross bars consisting of two end bars either of which is capable of acting as a keeper and as a tongue support, the middle bar being centrally disposed with respect to the two end bars and adapted to mount a tongue which can cooperate with either end bar. The invention contemplates the provision of a belt construction of this character wherein the tongue and the end bars are so arranged that the tongue lies equally flat against either end bar and wherein the middle bar operates as a pivot for the tongue and as a pivot for a securing clip by which the belt may be secured direct to the buckle.

The invention further contemplates a construction of this character which may be used with a reversible belt of the character wherein no tongue openings can be applied to the belt material. In this case, the tongue, except for the manner in which it grips the belt, cooperates with the cross bars and side bars in the same manner as in the type where the belt itself is provided with tongue openings.

Other and more detailed objects and advantages of the invention will appear more fully as the description proceeds, reference being had to the accompanying drawings wherein a preferred form of the invention is shown. It is to be understood, however, that the drawings and description are illustrative only, and are not to be taken as limiting the invention except insofar as it is limited by the claims.

45 In the drawings, Fig. 1 is a front view showing my improved belt buckle construction;

Fig. 2 is a sectional view on the line 2—2 of Fig. 1;

Fig. 3 is a view like Fig. 2 but showing the belt reversed;

Fig. 4 is a sectional view taken on the line 4—4 of Fig. 2;

Fig. 5 is a perspective view of the buckle frame with the tongue and belt attaching clip removed;

Fig. 6 is a perspective view of the belt attaching clip;

Fig. 7 is a front view similar to Fig. 1, illustrating a modified form of the construction;

Fig. 8 is a sectional view on the line 8—8 of Fig. 7;

Fig. 9 is a view like Fig. 8, but with the belt and buckle tongue reversed;

Fig. 10 is a sectional view on the line 10—10 of Fig. 8, and

Fig. 11 is a perspective view of the belt buckle frame shown in Fig. 7.

Referring now in detail to the drawings, the present invention is embodied in a belt buckle 10 which is adapted for use with a belt 11. The belt 11 is of a reversible type, that is, it is so constructed that either side may be worn on the outside and it may have different configurations or colors on the opposite sides, or, alternatively, it may be constructed of two different layers of material which would give these different appearances to the opposite sides.

The buckle itself comprises two side bars 12 and 13 and three cross bars 14, 15 and 16. The two cross bars 14 and 16 constitute end bars, and the bar 15 is half-way between the bars 14 and 16. All of the bars together make up a rigid rectangular frame which, as shown, is of one piece.

The side bars 12 and 13 are curved, as shown best in Figs. 2 and 5, and the bars 14, 15 and 16 lie on the outside of the curve with the bars 14 and 16 extending straight across and the bar 15 being bent inwardly as shown at 17 in Fig. 5. The curved side bars 12 and 13 thus provide guides between which the belt passes.

The belt 11 is attached to the central bar 15 by a belt attaching clip 18. This clip is shown in perspective in Fig. 6 and comprises a sheet of metal which is doubled upon itself and formed with a substantially round bar holding portion 19. The walls of the clip 18 are provided with integral prongs 20 and apertures 21, the apertures 21 being formed with inwardly projecting walls 21a cooperating with the prongs 20. The prongs 20 are pressed into the belt material and into the apertures 21 to secure the belt to the clip. The clip 18 has the bearing portion 19 cut out intermediate its ends, as shown at 22, so that a tongue 23 may also be mounted on the bar 15.

The tongue 23 consists of a metal strip. It has a ring 24 formed at one end thereof, the ring being bent around the bar 15. The tongue 23 is so constructed that its opposite surfaces 25

and 26 are alike, and each surface is provided with an indentation shown at 27 and 28. The end bars 14 and 16 have their edges 29 and 30 angularly shaped, and the indentations 27 and 28 are so shaped that the tongue lies flatly against either bar 14 or 16, as shown by Figs. 2 and 3. The free end of the belt 11 is provided with apertures 31 to receive the tongue 23.

It is believed to be evident from inspection of Figs. 2 and 3 how the tongue 23 may be moved to reverse the belt so that in one instance the tongue rests upon the bar 14 and the free end of the belt 11 passes beneath the bar 14 then over the center bar 15 and beneath the bar 16, which acts as a keeper. Then, when the belt is reversed to bring the other side out, the free end of the belt passes under the bar 16, thence over the bar 15 and under the bar 14 which acts as a keeper. Owing to the tongue and bar construction employed, the buckle presents the same appearance, regardless of which side of the belt is used as the outside.

Referring now to Figs. 7-11, in this form of the invention a buckle 10' is used with a reversible belt 11' which is of a type of material that cannot be provided with tongue apertures in the free end because of the characteristic of the material that causes it to rip if it is punched. Such a material is the so-called "reconstructed leather," which is made from ground up leather fiber and an adhesive. In this type of construction a belt attaching clip 18' is utilized for securing the belt to the middle bar 15' of the buckle. This clip is similar to that shown in the first form, having prongs 20' and apertures 21'. However, the apertures 21' are round and their walls are therefore of slightly different shape. The side bars 12' and 13' are of slightly different construction than in the first form of the device, in that they are flat with up-turned flanges 32 and 33. The cross bar 15' is preferably staked in the flanges 32 and 33 so as to provide an integral structure. The end bars 14' and 16' are substantially the same as in the first form except that no notches are provided for a belt tongue. In this form of the invention a special tongue 34 consisting of a flat metal sheet is pivoted on the cross bar 15' by means of a ring 35. The tongue 34 diverges outwardly from the ring 35 to provide side extensions 36 and 37 which overlap the adjacent side bars 12' and 13'. The free end of the tongue 34 provides a straight edge shown at 38 in Fig. 7 which cooperates with the adjacent straight edge of cross bar 14' or 16', depending upon the position of the tongue. The belt itself is pinched between the edge 38 of the tongue 34 and the adjacent cross bar so as to prevent slipping. As shown in Figs. 8 and 9, the tongue 34 may be readily reversed in the same manner as the tongue 23 in the first form of the device.

In both forms of the invention as described the reversible buckle consists of a simple frame made up of two side bars, two end bars and a central cross bar spaced midway between the end bars. The tongue and the belt attaching clip are so arranged on the central cross bar that the belt attaching clip centers the tongue

with respect to the side bars, and the tongue and clip are both free to be reversed so that either side of the belt may be placed outwardly in a simple and convenient way.

Having thus described my invention, what I claim as new and desire to secure by Letters Patent is:

1. A reversible belt buckle of the character described comprising a rigid frame having spaced side bars connected by three cross bars, two of said cross bars comprising end bars connecting the ends of the side bars and the third cross bar comprising a centrally disposed belt and tongue supporting bar, a straight tongue pivoted on said central bar and longer than the distance from the center bar to the end bars and having its opposite sides alike, whereby to engage either end bar in the same manner, and a belt attaching clip pivoted on said middle bar.

2. A reversible belt buckle of the character described comprising a rigid frame having spaced side bars connected by three cross bars, two of said cross bars comprising end bars connecting the ends of the side bars and the third cross bar comprising a centrally disposed belt and tongue supporting bar, a straight tongue pivoted on said central bar and longer than the distance from the center bar to the end bars and having its opposite sides alike, whereby to engage either end bar in the same manner, and a belt attaching clip pivoted on said middle bar, said tongue having oppositely disposed notches therein adjacent to the tip of the tongue to engage the adjacent edges of the respective end bars.

3. A reversible belt buckle of the character described comprising a rigid frame having spaced side bars connected by three cross bars, two of said cross bars comprising end bars connecting the ends of the side bars and the third cross bar comprising a centrally disposed belt and tongue supporting bar, a straight tongue pivoted on said central bar and longer than the distance from the center bar to the end bars and having its opposite sides alike, whereby to engage either end bar in the same manner, and a belt attaching clip pivoted on said middle bar, said end bars each having angular inner edges adapted to receive the tip of the tongue, and said tongue being recessed so as to lie flatly against the said edges of the end bars.

4. A reversible belt buckle of the character described comprising a rigid frame having spaced side bars connected by three cross bars, two of said cross bars comprising end bars connecting the ends of the side bars and the third cross bar comprising a centrally disposed belt and tongue supporting bar, a tongue pivoted on said centrally disposed bar, said tongue being longer than the distance between the centrally disposed bar and either end bar whereby to rest its tip upon either end bar, said tongue having oppositely disposed notches formed therein at the tip thereof, whereby to engage the adjacent edges of the respective end bars and cause the tongue to fit well against either end bar, and a belt attaching member on said centrally disposed bar.
